FIG. 3.

FIG. 4.

UNITED STATES PATENT OFFICE.

JOHN L. DOUGAN, OF PLANKINTON, SOUTH DAKOTA.

CARBURETER.

1,155,407.

Specification of Letters Patent.

Patented Oct. 5, 1915.

Application filed February 23, 1915. Serial No. 9,915.

To all whom it may concern:

Be it known that I, JOHN L. DOUGAN, a citizen of the United States, residing at Plankinton, in the county of Aurora and State of South Dakota, have invented certain new and useful Improvements in Carbureters, of which the following is a specification.

This invention relates to apparatus for mixing hydrocarbons, such as gasolene, with air before their admission to an internal combustion engine, and also to apparatus in which steam is mixed with the hydrocarbon and air to provide an explosive mixture.

The primary object of my invention is to provide a self-adjusting mixer or carbureter which is automatically and mechanically operated by the suction of the engine in such manner as to obtain a proper proportion of fuel and air at all engine speeds regardless of quick speed changes, variations in temperature and altitude or the specific gravity of the fuel.

A further object of the invention is to obtain a constant and uniform flow of fuel at all times and under all conditions.

Still another object of the invention is to provide means for economically and efficiently using grades of oil heavier than gasolene, such as crude oil, kerosene and the like.

In carrying out my invention with these objects in view, I employ an admission valve for the fuel which is connected with and operated by a piston operating in a cylinder or chamber which is closed to the atmosphere on one side of the piston and open to the mixing-chamber of the carbureter on the opposite side. This mechanism is so constructed and adjusted that the suction of the engine operates the piston to open more or less the fuel admission valve of the carbureter, the extent of the opening being in proportion to the degree of suction which produces a vacuum in the piston chamber on one side of the piston, which vacuum varies in degree proportionately with the amount of movement given to the piston and the suction power of the engine. The admission valve of the carbureter is preferably cone-shaped with its flat side or base exposed to fuel pressure which tends to close it and this force which tends to close the valve or resist its opening depends on the amount of pressure exerted by the fuel. When the fuel in the supply tank is at high level the pressure

on the flat face of the valve is greater and the valve is not open to so great an extent. When the fluid level is lower the valve opens more widely but flows past the valve at less speed. In this way a constant and uniform amount of fuel is fed to the engine whatever be the quantity of fuel in the supply tank. In this way, also, the usual float is dispensed with. This form of carbureter is serviceable when using gasolene or other light hydrocarbons as fuel and also when using heavier hydrocarbons, such as crude oil, kerosene and the like. In the latter case, however, I prefer to add to the carbureter a steam generator which supplies steam at a high temperature and which mixes with the fuel and air while being delivered to the mixing chamber of the carbureter. I also add to the carbureter hereinbefore described a valve controlling the admission of steam to the mixing chamber.

My improvements are illustrated in the accompanying drawings, in which—

Fig. 1 shows a vertical central section through a carbureter embodying my improvements, although of course it will be understood that the mixer may be arranged horizontally instead of vertically, as shown. Fig. 2 shows a transverse section on the line 2—2 of Fig. 1. Fig. 3 shows a vertical central section through an apparatus equipped with a steam generator and with valve mechanism controlling the admission of steam to the mixing chamber. Fig. 4 is a view on an enlarged scale, and in vertical section, of the valve mechanism shown in Fig. 3.

As before stated, the generator shown in Fig. 1 is especially intended for use when gasolene is used as a fuel. It has a mixing chamber A provided with a throttle valve a, and it also has an air inlet B controlled by valve b. The inner portion of the air chamber C is tapered, as shown, and into this chamber projects a fuel inlet pipe D which extends well up into the chamber C and has an annular space around its upper end at d for the passage of air to the mixing chamber. The upper end of the fuel pipe D is provided with a valve seat d' properly shaped to receive a cone valve E carried by a vertical rod e, jointed at e' to a lever F, pivoted at f to the casing and operating in the manner presently to be described. A piston chamber G communicates with the mixing chamber A through an opening g

2 and in this chamber is mounted a piston H having a rod h jointed at h' to the lever F and extending up through the top of the chamber G. A spring I surrounds the upper end of the rod h and is fastened to the casing and also to the upper end of the piston rod by a nut s. The spring tends to push the piston inward and by adjusting the nut s the tension of the spring may be regulated and this is done to regulate the flow of fuel and to adjust the valve mechanism for different grades of oil. When the engine is not running the piston H is at the lower end of the piston chamber, being moved to this position by the spring I. In starting the engine the valve b may be closed and the engine may be flooded with fuel and afterward the valve b is opened to the proper extent and the throttle valve a is properly adjusted. The inspiration or suction of the engine acts upon the piston H and tends to draw it upwardly and through the connections before described opens the fuel admission valve E to admit fuel to the mixing chamber. It will be observed that there is no communication between that part of the chamber G marked x in the drawings and the atmosphere, and as the piston is suitably packed to prevent leakage, when it rises or moves toward the mixing chamber a vacuum or partial vacuum is produced in the part x of the cylinder, the vacuum of course varying with the movement of the piston. In this way the engine is made to control the admission with great accuracy, the suction power being counterbalanced by the degree of vacuum formed and the mechanism is so adjusted that the fuel admission valve is opened and closed or controlled in such manner as to supply a uniform amount of fuel under all conditions. It will be observed that the admission valve E has a flat face exposed to fuel pressure. I find that by the use of such a valve I can dispense with the ordinary float valve in the fuel supply tank and yet obtain uniformity in fuel supply. When the fuel level is high in the supply tank greater pressure is exerted on the flat faces of the valve so that said valve is not opened to so great an extent as when the fuel level is lower, but when the fuel level is high fuel is made to pass more rapidly past the valve while when the fuel level lowers the flow of fuel is less rapid. At all times and under all conditions, however, the flow of fuel is uniform.

The carbureter before described is adapted for use with fuels of various kinds, but when heavy hydrocarbons, such as crude oil or kerosene are used I preferably employ means for supplying steam at high temperature to the mixer for the purpose of heating the hydrocarbons to render them more highly explosive.

65 In Fig. 3 I have shown a suitable apparatus

for this purpose. In most respects the carbureter is similar in construction to that shown in Fig. 1 and the parts are similarly lettered. The fuel supply pipe D is, however, surrounded by steam pipe J which 70 communicates with a boiler N having a water space n and flues T. Exhaust gases from the engine pass into the bottom of the generator and up through the flues T on one side of the partition Q and down through the flues T on the opposite side thereof, the gases passing out through the pipe O'. Water is admitted to the water space n through the pipe P, and the steam thus generated passes up through the pipe J. 80

S indicates a safety valve and R' indicates a door which when opened permits of a torch being inserted for starting the engine. After the engine has commenced to run the door may be closed and the generator may 85 be heated by the exhaust gases. Steam which passes through the pipe J heats the fuel in the pipe D and mixes therewith at the upper end of said pipe. In order to control the admission of steam to the mixing 90 chamber, I provide a valve R which in this instance is annular and surrounds the upper end of the fuel admission pipe D. This valve is provided with a yoke k which is secured to the valve rod e at k'. 95

j indicates the seat for the annular valve R and M indicates an annular guide or casing for said valve R. The arrangement is such that as the valve E opens and closes the annular valve R is correspondingly moved; 10 that it to say, when the valve E is in close contact with its seat d' the valve R is in close contact with its seat j. The casing M serves not only to guide the annular valve but protects the lower portion thereof from 10 steam pressure.

L indicates a disk on the valve rod e which serves to scatter the fuel immediately after it leaves the valve opening and causes it to be mixed thoroughly with the steam passing 11 the valve seat j. In this way the hydrocarbon is thoroughly heated and rendered suitable for mixing with the air to produce an explosive mixture. Furthermore, some of the steam enters the engine and helps to prevent pre-ignition and the formation of carbon in the engine.

While I have described in detail the best way now known to me of carrying out my invention, it will be understood that the details of construction may be considerably varied.

What I claim is:—

1. A carbureter provided with a mixing chamber for air and fuel, an air supply pipe leading to said mixing chamber, a fuel supply pipe concentrically disposed within said air supply pipe, a valve for controlling the admission of fuel to said chamber, a second chamber communicating at one end with the

mixing chamber and having an air tight closure at the other end, a piston operating in said second chamber, and means connecting said piston with said valve for opening and closing the same.

2. A carbureter provided with a mixing chamber for air and fuel, an air supply pipe leading to said mixing chamber, a valve controlling the passage of air through said pipe, a fuel supply pipe disposed within said air supply pipe, a valve for controlling the admission of fuel to said chamber, a second chamber located at one side of said fuel control valve and communicating at one end 10 with the mixing chamber and having its opposite end closed to the atmosphere, a piston operating in said chamber, a lever pivoted intermediate its ends to the wall of said mixing chamber and having its opposite 15 ends connected with said valve and said piston respectively for operating the same in unison.

3. In a carbureter having a mixing chamber for air and fuel, a fuel supply pipe, a 20 valve controlling the supply of fuel from said pipe, a second pipe, a valve seat car-

ried thereby, an annular valve between said pipes, and means for simultaneously operating both of said valves.

4. In a carbureter having a mixing chamber, a fuel supply pipe, a valve for controlling the supply of fuel from said pipe, a second pipe concentrically positioned around said first mentioned pipe, a valve seat carried thereby, a guide casing carried by said 35 inner pipe, a valve in said casing, and means for operating said valves in unison.

5. In a carbureter in combination, a fuel supply pipe, a valve controlling the fuel supply from said pipe, a steam generator, a 40 second pipe surrounding said first mentioned pipe and communicating with said generator, an annular valve located between said pipes, and connecting means between said valves for causing the same to move in unison. 45

In testimony whereof, I have hereunto subscribed my name.

JOHN L. DOUGAN.
